MODIFIED HEAD FOR SOAP INJECTOR UNIT

The present invention relates generally to injection means for positive displacement pumps, and more particularly to fluid injection means arranged for the induction of fluid into the pumping chamber of a positive displacement pump having its inlet coupled to a source of fluid under pressure. Normally, the induction of fluid into a positive displacement pump occurs during the suction stroke of the piston, and accordingly, such means may be utilized only when the fluid supply is operated under modest pressure. The present invention permits the induction to occur when the supply is maintained at a substantial pressure. In this device, the material that is being induced into the pumped fluid is stored in a reservoir which is not operated under any pressure, and thus no unusual features are required in the induction system.

In the past, various attempts have been made for inducing fluid flow into a pressurized cylinder or chamber. Frequently these devices are used for the purpose of lubrication, and may be utilized in combination with pressurized chambers or reservoirs. In other devices, venturis may be interposed in the pressure line and the venturi, together with its pressure drop, will cause the induction of fluid from a reservoir into the stream. It is requisite, of course, that a venturi operates on the basis of fluid velocity, and accordingly high velocities are required in order to obtain any quantity of injected fluid into the line. The systems may cause considerable back pressure to develop, and may be undesirable for interposing in the line for a number of reasons.

Positive displacement pumps such as reciprocating piston pumps are widely utilized. In many applications of these pumps, it is desired to inject a certain quantity of a fluid into the pumped fluid for any of a variety of purposes. One such purpose is the introduction of a controlled quantity of soap, the soap being introduced into the system when it is desired to provide a pressurized washing system such as, for example, in an automobile-washing system.

In a conventional system, wherein water is being utilized, it is frequently desirable and possible to couple the system directly to the line source. Such a line source may be at an elevated pressure, such as in the range of 50 p.s.i. up to about 80 p.s.i. In these installations, therefore, the incoming water would enter the system at this elevated pressure, and the present invention makes it possible to provide the pump with a modified head to control the fluid flow and permit induction from a reservoir supply at atmospheric pressure into a pump with the inlet coupled to a source at elevated pressure.

The apparatus of the present invention is highly adapted for use in connection with water supplies at elevated pressure. In instances where the line pressure is at modest levels, coupling directly to the line source is permissible, and where the line pressure is at a highly elevated pressure, such as at about 100 p.s.i., for example, it may be necessary to utilize a pressure regulator to permit the injector to properly function.

The modified head design of the present invention is particularly adapted for use in connection with the injector system disclosed and claimed in our copending application, Ser. No. 838,195, filed July 1, 1969, and entitled "LIQUID INJECTOR ASSEMBLY FOR PISTON PUMPS," and assigned to the assignee of the present invention.

The system of the present invention is particularly designed for use in combination with positive displacement pumps equipped with an injector system including a pilot or regulator valve which controls the communication between the pumping chamber and the supply reservoir of the injected fluid. Poppet valve means are preferably provided between the injection chamber and the pumping chamber of the pump, in order to isolate the injected fluid during the pressure stroke of the pump. A further feature of such an injector is the presence of an injector baffle means which is interposed between the injection chamber and the pumping chamber, this baffle means providing accurate metering between the pumped fluid and

the injected fluid. The positive displacement pump, when coupled to a line source under substantial pressure, requires an additional baffle means in the pumping chamber at a point between the orifice coupling the line source to the pumping chamber, and the piston and induction means. As a matter of convenience and for preferred operation, this baffle means is interposed in the head of the pump and forms a reduced channel or barrier for fluid entering the pumping chamber from the orifice of the line source.

10 Therefore, it is an object of the present invention to provide an improved induction means or apparatus for use in combination with a positive displacement pump coupled to a line source at elevated pressure, the induction means being in communication with the pumping chamber of the pump and being adapted to induce or inject controlled quantities of fluid into the pumping chamber of the pump, the pumping chamber having a baffle separating or partially isolating the orifice of the line source from the main chamber portion of the pumping chamber.

15 20 It is a further object of the present invention to provide an improved induction means for use with positive displacement pumps coupled to a line source at elevated pressure, the induction means being coupled directly to the pumping chamber and adapted to inject fluid during the suction stroke of the positive displacement pump.

25 30 Other and further objects of the present invention will become apparent to those skilled in the art upon a study of the following specification, appended claims, and accompanying drawing where:

35 FIG. 1 is a vertical sectional view taken through the center of a positive displacement pump, and illustrating the induction means of the present invention arranged in combination with the positive displacement pump and showing the improved baffle means secured to the head of the pump and partially isolating the line source inlet orifice from the main portion of the pumping chamber;

40 FIG. 2 is a detail elevational view of the improved head which is used in the system shown in FIG. 1; and

45 FIG. 3 is a vertical sectional view taken along the line and in the direction of the arrows 3—3 of FIG. 2.

50 In accordance with the preferred modification of the present invention, and with particular attention being directed to FIG. 1 of the drawing, the injection system generally designated 10 is shown coupled to and in combination with the positive displacement pump generally designated 11. The pump includes the conventional housing 12 incorporating a supply or inlet orifice 13 along with a discharge orifice or the like 14. The inlet 13 and outlet 14 are appropriately threaded so as to permit convenient coupling to supply conduits and discharge conduits, the inlet being arranged to be coupled to a line source under substantial pressure. The basic operation of the pump illustrated in FIG. 1 is described in detail in U.S. Pat. No. 3,138,890 to H. J. Sadler, et al., entitled "PISTON TYPE PUMP" and assigned to the same assignee as the present invention, and while the structure will be explained in some detail here, reference is made to the Sadler, et al. patent for a thorough description of the pump structure. The pump body 12 is provided with a pair of heads, such as the heads 16 and 17, these heads being arranged at opposed ends of the inlet channel 18 and the outlet channel 19. It will be observed that the head 16 is provided with a baffle means generally designated 20 for effecting a partial isolation or separation of the orifice of the line source from the main chamber portion of the variable volume pumping chamber. Appropriate inlet valves are provided at 21 and 22, and appropriate outlet valves are provided at 23 and 24. In order to provide the variable volume pumping chambers 25 and 26, reciprocating piston

60 65 70 75 assembly generally designated 30 is provided, this system including pistons 31 and 32. An eccentric drive means is shown as at 33, the drive means including an eccentric pin member 34 spaced from the drive cam or race 33 by means of a plurality of roller bearings such as are shown at 35. A suitable connecting yoke, not shown, is utilized to draw the individual

pistons inwardly of the system during the pumping strokes. Also, as is conventional, an expandable piston cup is utilized as at 37, the cup being held against the walls of the cylinders, such as the cylinders 38 by means of an O-ring as at 39.

It will be appreciated that the induction or injection means illustrated herein is typical of one of many which may be utilized in combination with the positive displacement pump with the modified pumping chamber, the system being shown in combination with the pump herein for purposes of a better understanding of the overall concept. For example, the system can function in a variety of pump structures, including positive displacement pump structures having one piston, two pistons, or even a greater number of pistons. The pistons may be axially opposed, or may be arranged along parallel axes. It is preferable, however, that each reciprocating piston be provided with a separate pumping chamber, such as the pumping chambers 25 and 26 which are each provided with individual reciprocating pistons 31 and 32 in conjunction therewith. The baffle means 20 is normally employed in conjunction with each head provided with or coupled to an injector system.

Particular attention is now directed to the induction means 10 which is illustrated in FIG. 1, the induction means being coupled to supply reservoir 50 by conduit 51. In order to provide appropriate control of the flow of fluid to be induced, a solenoid valve or the like may be utilized, such as is shown at 52, with appropriate control lines, as necessary, being utilized. The induction means 10 comprises a body member 54 which has a bore 55 extending therethrough, bore 55 having a coun-

the inlet to the pump is under modest or moderate pressure.

Attention is now directed to FIG. 2 of the drawing wherein the interior of the head 16 is illustrated. The baffle means generally designated 20 includes a pair of abutment members 85 and 86 which form a flow channel such as is shown adjacent the arrow 87. In this connection, the inlet area or zone is generally at 88, while the discharge is in the area 89. The reciprocating piston is located adjacent the zone shown at 90.

The annular area shown at 91 is for accommodating an O-ring seal for sealing the head 16 to the body member 12.

It will be observed that the abutment members 85 and 86 present rounded corners which are for the purpose of reducing cavitation and turbulence as the fluid flows from the inlet to the pumping chamber. The gap area or restriction slot is generally related to the capacity of the pump and the inlet valve, the restriction having a smaller area of free flow than the inlet valve when in full-open position. Thus, it is possible for the reciprocating piston to create a vacuum during the suction stroke, and this is possible even at incoming line pressures of from up to 50 p.s.i. or higher. With this baffle zone being available, the material introduced into the system through the injector assembly 10 is uniform, predictable, and consistent.

FIG. 3 illustrates the head with the baffles interposed for controlling flow. It will be observed that the individual abutment members 85 and 86 extend to the base plane of the head such as at 91, for example.

As a typical design for the baffle generally designated 20, the following information is provided:

30

Stroke	Piston area, sq. in.	Factor, cu. in. to gal.	2 pistons	R.p.m.	G.p.m.	Width of channel 87, in.	Depth of channel 87, in.
.198-----	.785	.004329	2	1,750	2.36	0.187-0.197	532
.190-----	.785	.004329	2	1,750	2.26	0.187-0.197	532
.228-----	.785	.004329	2	1,750	2.71	0.187-0.197	542
.220-----	.785	.004329	2	1,750	2.62	0.187-0.197	542
.284-----	.785	.004329	2	1,750	3.38	0.187-0.197	542
.276-----	.785	.004329	2	1,750	3.28	0.187-0.197	542

40

terbore portion as at 56 for accommodating the control valve or pilot valve means generally designated 57. Valve 57 includes a pin member 58 which is coupled to the knurled knob portion 59. Knurled knob 59 has a threaded member 60 which is threadably engaged with the bore extension 61, thus controlling the relative dispositions of the tapered tip portion 62 of the pin member 58 relative to the seat area 63. This provides a controllable orifice for the flow of material from the supply reservoir to the pumping chamber 25.

It will be appreciated that a variety of means can be utilized to couple the induction means to the pump body. In the device shown herein, a threaded collar nut 65 having a flanged portion as at 66, is utilized to engage the collar 67 of the body 54, and thereby retain it in appropriate disposition on the head member 16. A threaded attachment is generally preferred, thus making it possible for the induction means to be coupled to the supply reservoir at any angular disposition.

Attention is now directed to the end portion of the injection means shown generally at 70, this member including a body with two segments, including segment 71 and segment 72, O-ring 73 being utilized to seal the induction means within the head 16. Poppet valve 75 is shown operating against the seat or orifice area as at 76, valve 75 being resiliently biased by means of the spring 78, and accordingly being adapted to open upon the suction stroke of piston 31, and close upon the pressure stroke of that piston.

The arrangement is provided with a baffling orifice as at 79, this orifice isolating the chamber area 80 from the pumping chamber 25. Thus, turbulent flow or the like within the pumping chamber 25 will not present any adverse affects upon the induction flow into chamber 25 from the induction means 10. Furthermore, it has been found possible that with the use of the baffle member, induction of fluid may occur even though 75

For operating at line pressures, of up to about 35 p.s.i., the above figures are valid. If higher line pressures are to be encountered, the channel should be somewhat more restricted in order to prevent the incoming pressure from oversupplying the pumping chamber during the suction stroke of the piston. As an alternative, a pressure regulator may be employed to hold the line pressure at the pump to below about 30 to 35 p.s.i.

It will be appreciated that the structures shown here may be utilized in a variety of combinations, and with a variety of pumping structures, and that the examples given herein are for purposes of illustration only.

What is claimed is:

1. In combination with a positive displacement pump having a body with wall means and cover means defining a pumping chamber, a reciprocating piston disposed in a cylinder communicating with said chamber, a source of fluid under pressure being coupled to said pump through a supply conduit, inlet and outlet orifices communicating with said chamber and having inlet and outlet valve means respectively for intermittent isolation of said chamber from a supply conduit and a discharge conduit respectively;

a. induction means communicating with said pumping chamber for inducing fluid flow into said pumping chamber for discharge through said discharge conduit and including:

1. induction inlet means coupling a supply reservoir of fluid to be introduced into said pumping chamber and communicating with said chamber through a certain induction orifice; and
2. control valve means for controlling the flow of fluid from said supply reservoir to said induction orifice;
- b. baffle means formed along the inwardly directed surface of said cover means and being integral therewith, and par-

tially isolating said cylinder and said induction orifice from said inlet orifice, said baffle means substantially impeding the flow of fluid from said source of fluid under pressure to said cylinder so that upon each suction stroke of said piston, the pressure of said pumping chamber falls to a level below atmospheric.

2. The combination as defined in claim 1 being particularly characterized in that said baffle means comprises a pair of opposed abutments arranged in spaced apart relationship so as to define a flow channel therebetween.

3. In combination with a positive displacement pump having a body with wall means and cover means defining a pumping chamber, a reciprocating piston disposed in a cylinder communicating with said chamber, a source of fluid under substantial line pressure being coupled to said pump through a supply conduit, inlet and outlet orifices communicating with said chamber and having inlet and outlet valve means respectively for intermittent isolation of said chamber from a supply conduit and a discharge conduit respectively;

a. induction means communicating with said pumping chamber for inducing fluid flow into said pumping chamber for discharge through said discharge conduit and including:

1. induction inlet means coupling a supply reservoir of fluid held at substantially atmospheric pressure and to be introduced into said pumping chamber and communicating with said chamber through a certain induction orifice; and

2. control valve means for controlling the flow of fluid from said supply reservoir to said induction orifice;

b. baffle means formed in said chamber and partially isolat-

ing said cylinder and said induction orifice from said inlet orifice, said baffle means substantially impeding the flow of fluid from said source of fluid under pressure to said cylinder so that upon each suction stroke of said piston, the pressure of said pumping chamber falls to a level below atmospheric.

4. The combination as defined in claim 1 being particularly characterized in that said baffle means comprises a pair of opposed abutments arranged in spaced apart relationship so as to define a flow channel therebetween.

5. The combination as set forth in claim 1 being particularly characterized in that the free flow area of said baffle means is less than the free flow area available in said inlet valve.

6. The combination as defined in claim 3 being particularly characterized in that said opposed abutments have generally arcuately rounded confronting surfaces forming a narrowed channel therebetween.

7. The combination as defined in claim 1 being particularly characterized in that said induction means includes:

a. check valve means disposed in a second orifice and in communication with said first orifice and arranged to open upon the suction stroke and close upon the pressure stroke of said reciprocating piston; and

b. injection chamber means disposed between said check valve means and said pumping chamber and having a third orifice in direct communication with said pressure chamber and having baffle means interposed between said third orifice and said injection chamber for substantially isolating said injection chamber means from said pumping chamber.
